UNITED STATES PATENT OFFICE.

CLEMENT I. AMEY, OF TORONTO, ONTARIO, CANADA.

TRACK LIFTING, LEVELING, BALLASTING, AND TAMPING MACHINE.

No. 857,572.

Specification of Letters Patent.

Patented June 25, 1907.

Application filed December 31, 1906. Serial No. 360,287.

To all whom it may concern:

Be it known that I, CLEMENT ISRAEL AMEY, of the city of Toronto, in the county of York and Province of Ontario, Dominion of Canada, have invented certain new and useful Improvements in Track Lifting, Levelling, Ballasting, and Tamping Machines; and I hereby declare that the following is a full, clear, and exact description of the same.

This invention relates to a machine which will mechanically execute the work manually performed by a gang of navvies in railroad construction and track leveling operations. To perform the above named operations, it is necessary to provide the machine with a means which will mechanically lift the track rails and ties to any reasonable height, and level them and hold them in their lifted and leveled position until the ballasting and tamping operations are completed. It is also necessary to provide the machine with a ballasting means which will mechanically move the ballast from the sides of the road bed and deposit it at the sides of the ties, across their entire length either before or after the track rails and ties have been raised and leveled by the first mentioned means. It is also necessary to provide the machine with a tamping means which will pick the ballast under the ties. The ballasting and tamping means are carried by a car specially constructed for the purpose, and are operated by a motor mounted thereon. The track lifting and leveling means may be carried by the main car but it is preferable to carry it by an auxiliary car capable of being positioned on the road bed either manually or by the main car.

For a full understanding of the invention reference is to be had to the following description and to the accompanying drawings, in which:

Figure 1, is a side elevation of the complete apparatus, showing the relative position of the various parts. Fig. 2, is a plan view of the construction shown in Fig. 1. Fig. 3, is an end elevation. Fig. 4, is a side elevation of the tamping mechanism, but on a larger scale than in the preceding views. Fig. 5, is an end elevation of the construction shown in Fig. 4, and on the same scale as the latter. Figs. 6, and 7, are respectively side and end elevations of the traveler for the tamping mechanism. Fig. 8, is a vertical section of the lifting and lowering drum of the tamping mechanism. Fig. 9, is a verti-

cal section of the tamping mechanism. Fig. 10, is a vertical section of the track lifting and leveling mechanism. Fig. 11, is a vertical section of the same taken at right angles to Fig. 10. Fig. 12, is a plan view of the construction shown in Figs. 10, and 11. Fig. 13, is an end elevation of the ballasting apparatus. Fig. 14, is a side elevation of the construction shown in Fig. 13. Fig. 15, is a plan view of the ballasting apparatus. Fig. 16, is a detail view of one of the elevators. Fig. 17, is a vertical section of the driving sprocket wheel for the elevator belts.

Like characters of reference refer to like parts throughout the specification and drawings.

In the construction of a road bed of a railroad, it is customary to employ steam shovels and navvies to perform the grading and sloping work when preparing the surface for the ties. When the ties are laid, and the track rails spiked to them, the leveling and ballasting operations are commenced. In the execution of the leveling and ballasting operations it is necessary to employ a track lifting gang to raise the track and ties to the required elevation and level, and a shoveling gang to throw the ballast into the space between the ties and tamp it into a compact mass beneath them, to maintain the ties and track rails at the elevation and level to which they have been raised by the track lifting gang.

The present invention relates to a machine which will successively perform the operations of lifting and leveling the track rails, depositing the ballast between the ties, and tamping it under them, the operations of ballasting and tamping being performed simultaneously at progressive places.

The track lifting part of the apparatus, comprises a car of light construction similar to the ordinary hand car employed in railroad operations, and which may be described as consisting of parallel side sills *a* extending lengthwise of the car, two transverse tie plates *a'* rigidly connected at right angles to the side sills vertically above the car axles, journal boxes *b* rigidly connected to the tie plates *a'*, axles *c* journaled in the boxes *b*, car wheels *d* mounted on the axles, and cross sills *e* rigidly bolted at right angles to the top surfaces of the side sills and overhanging the latter beyond the outer sides of the track rails.

Contained between the cross sills beyond

- the plumes of the outer sides of the track rails are air cylinders *f*. Vertically movable in the air cylinders *f* are pistons *g* and connected to the pistons *g* and extending downwardly through the air cylinders in the direction of the road bed are plungers *h* having at their lower ends feet *i* to engage with the road-bed. The feet *i* are connected to the plungers by ball and socket joints *j* so that they will automatically adapt themselves to the surface of the road-bed when they are forced into contact with it by the plungers. Extending through the cross sills vertically above the track rails are eye bolts *k* and suspended from the eye bolts are rail grips *l* having sliding locking clamps *l* to fasten them against the rails. Each air cylinder is provided with a valve controlled air pipe *m* connected by a flexible pipe *o* with the air pump *p* carried on the main car *q*. When the valves *p*³ and *p*⁴ for both air pipes *m* are simultaneously opened, both cylinders are simultaneously operated. The valve for either one of the air pipes can be closed, and the operation of its cylinder can then be prevented during the operation of the other cylinder.
- The car is moved to that part of the track to be lifted and the rail grips *l* are locked in engagement with the webs of the track rails, below the tread thereof, by the sliding locking clamps. When the rail-grips are locked to the track rails, the valves for the air pipes *m* are opened and both air cylinders are simultaneously operated. The air in the air cylinders forces downward the pistons and the plungers, until the downward movement of these parts is arrested by the resistance of the road bed to the feet of the plungers. The continued action of the air in the air cylinders then raises the air cylinders from the pistons. The air cylinders being rigidly bolted to the cross sills of the car, necessarily lift the car. The car being clamped by the rail-grips to the track rails lifts the track rails and ties with it as it is raised by the upward movement of the air cylinders. When the track rails and ties are raised to their required elevation the controlling valves for the air pipes leading to the air cylinders are closed, and the air supply to the air cylinders is shut off, with the air confined therein, to hold the track rails and ties at the elevation to which they have been raised. The level of the track rails is determined by a spirit level *r* secured to one of the cross sills and the accurate level of the track rails may be attained by selectively shutting off the air supply of one cylinder in advance of the shutting off the air supply of the other.

The construction of the track leveling and track lifting mechanism may be varied within the scope of the appended claims without departing from the nature of the invention, 65 the essential feature of which is to employ a

mechanically operated means sensitive to the control of the operator to raise the track rails to any reasonable required height, level them, and hold them at their elevated and leveled position until the succeeding operations are completed. When the succeeding operations are completed the controlling valves for the air pipes are opened to relieve the cylinders of the air pressure and permit of the rail grips being released from the track rails, so that the car can be moved to a progressive place on the track rails. The track lifting car may be moved either manually or otherwise and progresses along the track in advance of the main car *q* to raise the track rails in advance of the ballasting and tamping mechanisms.

As shown in the drawings the air cylinders are connected by air pipes *m* and flexible pipe *o* with the air pump *p* mounted on the main car with the valves *p*³ and *p*⁴ controlling the passage of the air from the flexible pipe *o* through the air pipes *m* to the air cylinders. The valves *p*³ and *p*⁴ are of the usual type of three way valves which can be operated to permit of the unobstructed flow of air from the air pumps to the cylinders, or can be closed to prevent the flow, or can be actuated to exhaust the air from the air cylinders while closing the supply from the air pipe. Rigidly connected to the main car *q* and extending in advance of it at a suitable height above the track rails, is a horizontal crane, which may be described as comprising two still riveted girders *s* arranged in horizontal and parallel plates and separated by an unoccupied intervening space. Rigidly bolted to the free ends of the girders *s* is a channel beam *u* provided with a shaft bearing *v*. Bolted to the girders *s* on the inner side of the channel beam *u* is a channel beam *x* having a shaft bearing *y* aligned with the shaft bearing *v* and separating the channel beams *u* and *x* is a space for the elevator *w*.

Journalized in the shaft bearings *v* and *y* is a driven shaft *z* having at its inner end a spur wheel *a'* which meshes with a spur wheel *b'* mounted on the driving shaft *c'*. The driving shaft *c'* is journalized in a shaft bearing *d'* connected to the channel beam *e'* and in a shaft bearing *f'* connected to the channel beam *g'*. The channel beam *e'* is bolted to the girders *s* adjacent to the channel beam *x*, but is separated from the last mentioned channel beam by the space in which the spur wheels *a'* and *b'* revolve, and the channel beam *g'* is bolted to the girders *s* adjacent to the channel beam *e'* but is separated from the channel beam *e'*, by the space for the elevator *h'*.

Each of the elevators *w* and *h'* consists of two parallel channel beams *a'* rigidly bolted together by tie plates *i'*, elevator shafts *j'* journalized in the channel beams *a'*, elevator wheels *k'*, mounted on the elevator shafts, ele- 130

veyor belts p' traveling around the elevator wheels, elevator buckets m' pivoted to the elevator belts and arranged to be tripped at any selective place in their travel.

5 In the channel beams o' are longitudinally disposed slots p' in which are contained guide blocks q' . The guide blocks q' are loosely mounted on the driving shaft e' and driven shaft z' to turn with the channel beams o' as the latter vary their inclination. The purpose of the guide blocks is to guide the sliding movement of the elevators during their adjustment to the ballast, and a further purpose is to prevent the sides of the slots p' coming into contact with the driving and driven shafts. Mounted on the driving and the driven shafts are double sprocket wheels r' which engage the elevator belts p' and transmit motion from the driving and driven shafts thereto. The double sprocket wheels engage the elevator belts above and also below the driving and driven shafts, and by such engagement with the belts hold the elevators without other assistance in their adjusted position. The elevators are adjusted as follows: to lower the elevators toward the ballast—the elevator belts at the lower sides of the elevators are thrown out of engagement with the teeth of the sprocket wheels r' , and the friction brakes s' are brought into engagement with the elevator shafts at the upper ends of the elevators to prevent revolution of the elevator wheels and the travel of the elevator belts. The revolution of the sprocket wheels r' being continued the engagement of their teeth with the elevator belts at the upper sides of the elevators, move the elevator belts and the other elevator parts in a downward direction until the elevator belts at the lower sides of the elevators are again permitted to engage with the sprocket wheels. The upward adjustment of the elevators can be effected in the same way by throwing the elevator belts at the upper sides of the elevators out of engagement with the teeth of the double sprocket wheels r' and applying the friction brakes s' and permitting the elevator belts at the lower sides of the elevators to remain in engagement with the teeth of the double sprocket wheels r' .

Connected to the lower ends of the elevators are bails t' and attached to the bails are cables u' which pass over pulleys v' suspended from outriggers w' connected to the sides of the girders s and tightened by winding shafts x' to support the elevators in their adjusted positions and relieve the sprocket wheels r' of the principal part of the weight of the latter.

65 The ballasting operations usually succeed the raising and leveling of the track rails and ties, but it is not necessary that the operation of the parts of the machine should be confined to any selected order of precedence,

as the operation of the ballasting mechanism could begin prior to the raising and leveling of the track rails and ties or could be carried on co-incident therewith.

During the suspension of the ties and track rails the tamping mechanism is brought into action to force the ballast under the ties and tamp it into a substantially solid and concrete mass.

The tamping mechanism is carried by a crane car a'' having car wheels y' traveling on opposite sides of a track beam z' bolted to the crane of the main car between the elevators and the fixed end of the crane. Fastening together the lower ends of the side plates y'' of the crane car are eye bolts b'' and hanging from the eye bolts b'' are supporting hooks e'' . Suspended from the supporting hooks e'' are the lifting and lowering cylinders d'' . Within the cylinders d'' are pistons e'' having piston rods f'' which project beyond the lower ends of the cylinders. Forming part of the lower ends of the piston rods f'' on the outer sides of the cylinders are hooks g'' from which are suspended the bails of the tamping mechanism. Between the pistons e'' and the bottom heads of the cylinders d'' are compression springs d' . Two cylinders d'' are employed one at each end of the tamping mechanism and when the air is turned into the cylinders from the valve controlled air pipes h'' , the pistons e'' are actuated to lower the piston rods and the parts suspended therefrom until the shovels of the tamping mechanism are properly positioned to engage the ballast and pack it under the ties. Suspended from the hooks g'' by bails i'' are two channel beams j'' . The channel beams j'' are rigidly riveted together by tie plates j' to form a supporting frame for the shovel levers k'' . The shovel levers k'' are rockable upon spring tensioned bolts l'' extending through the channel beams j'' and through tapering holes in the shovel levers.

As shown in the drawings the heads m'' of the spring tensioned bolts are within the supporting frame and at a considerable distance from the inner sides of the channel beams j'' . Coiled on the spring tensioned bolts l'' between the heads m'' and the adjacent sides of the channel beams are tension springs o'' , so adjusted as to yieldingly hold the shovel levers against the outer sides of the channel beams j'' .

The tapering holes p'' permit the shovel levers to rock on the spring tensioned bolts l'' during the tamping operation hereinafter described, and the construction of the spring tensioned bolts permits all or any of the shovel levers to move outwardly from the supporting frame when the inward movement of the shovel blades is resisted by an immovable obstacle.

At the upper ends of the shovel levers k'' 130

- ure eye beams q'' and opposed to the eye beams q'' are a series of expanding cylinders r'' . The expanding cylinders are connected with and supplied from the air pipes s'' .
- 5 The air pipes s'' are supplied with air from the air pump p and deliver the air to the expanding cylinders. One of the eye beams q'' is opposed to the closed end of the expanding cylinders r'' and the other end is opposed to 10 the piston rods t'' connected with the pistons u'' working within the expanding cylinders. When the air is turned into the expanding cylinders, the expanding cylinders operate to force the eye beams q'' asunder and this movement of the eye beams forces the upper ends of the shovel levers outward and presses the shovel blades v'' under the ties. This action of the shovel levers and shovel blades tamps the ballast under the ties in the same manner as it would be tamped by manual labor, until it has been packed into a concrete mass.
- To produce the tamping action of the shovel blades and shovel levers, the air is 15 alternately admitted and exhausted from the expanding cylinders by the opening and closing of the controlling valves w'' for the air pipes s'' which may be of any of the ordinary types of valves in common use.
- 20 The lifting and lowering cylinders d'' are connected with the air pump p by valve controlled air pipes h'' and in the operation of this feature of the invention the air is admitted through the valve controlled air pipes h'' to the lifting and lowering cylinders d'' until the shovel blades extend below the tie under which the ballast is to be tamped and on opposite sides thereof.
- 25 When the shovel blades are properly positioned at the sides of the tie, the air is admitted to the expanding cylinders to expand the upper ends of the shovel levers so that the shovel blades will pass beneath the tie and pack the ballast under it. The air is then exhausted from the expanding cylinders to permit of the contraction of the upper ends of the shovel levers and the expansion of the lower ends. This action of the 30 expanding cylinders and shovel levers and shovels is followed by the exhausting of the air from the lifting and lowering cylinders. The compression springs d'' then restore the pistons to their initial position within the cylinders and lift the shovels and shovel levers above the ballast. The air is again admitted to the lifting and lowering cylinders to lower the shovel levers and shovels into contact with a fresh supply of ballast, and the air is again admitted to the expanding cylinders to again actuate the shovel levers and shovels. The air is then again exhausted from the expanding cylinders and from the lifting and lowering cylinders, and a repetition of these operations is continued

until the ballast is properly tamped. In the event of one of the shovel blades coming into contact with an immovable body such as a large stone or a stump during the operation of the tamping mechanism, the engagement of the shovel blade or blades with such obstacle will not impede the operation of the remaining shovel blades and shovel levers by reason of the spring tensioned bolt or bolts t'' yielding to permit of such shovel blade or blades remaining inactive against such obstacle, while the upper end of its or their shovel lever or levers are distended by the expanding action of the expanding cylinders, the spring tensioned bolts t'' moving outwardly toward the channel beams j'' until the tension springs o'' have been fully compressed.

Mounted on the main car q is an engine y'' from which motion is transmitted to the car wheels z'' by a suitable transmission means A to propel the car in a forward direction. From the engine y'' motion is also transmitted by a suitable transmission means B to the air pump p to actuate it to supply the compressed air to the lifting and tamping mechanisms, and from the same engine motion is also transmitted by a suitable transmission means C to the driving shaft e for the elevator mechanism.

The track lifting and leveling car may be connected with the main car q and propelled by it during the progress of the latter or it may be positioned manually by those operating the various parts of the mechanism. The ballasting and tamping mechanisms are carried however by the crane attached to the main car and the main car is advanced a distance of one tie on each operation of the co-acting mechanisms to enable the ballasting mechanism to deposit the ballast and the tamping mechanism to place the ballast under the tie, the tamping mechanism being preferably positioned manually to enable the shovel blades to accurately descend at the sides of the tie under which the ballast is to be placed.

As shown in the drawings there are four single shovel blades at each side of the tie intermediate the track rails and a double shovel blade at each side of the tie between the track rails and the tie ends but the number of the shovel blades may be varied to meet the requirements of the apparatus and the conditions under which it is operating.

Having thus fully described my invention, what I claim as new and desire to secure by Letters Patent is:

1. The hereinbefore described apparatus comprising a tamping means consisting of a tamper frame, tampers, spring pressed fulcrums rockably and yieldingly connecting the tampers to the tamper frame, means for raising and lowering the tamper frame, and

operable means engaging the upper ends of the tampers to press them outward, and the lower ends inward.

2. The hereinbefore described apparatus comprising a tamping means consisting of a tamper frame, two sets of tampers arranged on opposite sides of the tamper frame, spring pressed fulcrums rockably and yieldingly connecting the tampers to the tamper frame, means for raising and lowering the tamper frame and tampers, and operable means engaging the upper ends of the tampers to press them outward, and the lower ends inward.

15 3. The hereinbefore described apparatus comprising a tamping means, means for raising and lowering the tamping means relatively to the road bed, other means for actuating the tamping means to move beneath the tie when performing their tamping functions, and a ballasting means.

4. The hereinbefore described apparatus comprising a tamping means, consisting of two sets of tampers arranged to operate on 25 opposite sides of the tie, means for raising and lowering the tamping means, other means for actuating the tampers to move beneath the tie when performing their tamping functions, and a ballasting means.

30 5. The hereinbefore described apparatus comprising a ballasting means consisting of two elevators arranged at opposite sides of the road bed and extending transversely across the same, and means for actuating the elevators whereby the ballast may be deposited at the sides of the tie from end to end thereof.

6. The hereinbefore described apparatus comprising a ballasting means consisting of 40 two elevators arranged at opposite sides of the road bed, and extending transversely across the same, means for actuating the elevators whereby the ballast may be deposited at the sides of the tie from end to end thereof, 45 and a tamping means to force the ballast under the ties.

7. The hereinbefore described apparatus comprising a ballasting means consisting of 50 two elevators arranged at opposite sides of the road bed, and extending transversely across the same, means for actuating the elevators whereby the ballast may be deposited at the sides of the tie from end to end thereof, and a tamping means consisting of a 55 set of tampers, means for simultaneously raising and lowering all the tampers of the set, and other means for simultaneously actuating the tampers to press the ballast under the ties.

60 8. The hereinbefore described apparatus comprising a track lifting carriage, rail grips carried thereby, and a carriage lifting means consisting of two cylinders connected to the track lifting carriage, pistons movable within 65 the cylinders, piston rods for the pistons, ex-

tending beyond the lower end of the cylinders, feet adjustably connected to the pistons, and pneumatic means connected with the cylinders.

9. The hereinbefore described apparatus 70 comprising a track lifting carriage, rail grips carried thereby, clamps for locking the rail grips, lifting cylinders carried by the track lifting carriage, pistons for the lifting cylinders, piston rods for the pistons, projecting 75 beyond the lower ends of the cylinders, feet adjustably connected to the lower ends of the pistons, and means for actuating the pistons, and cylinders to raise the track lifting carriage.

10. The hereinbefore described apparatus comprising a main carriage, a motor carried thereby, and a ballast lifting means consisting of two elevators, working from opposite sides of and transversely across the track 85 bed, and arranged to carry the ballast from the sides thereof, and deposit it at the sides of the ties along the length thereof.

11. The hereinbefore described apparatus comprising a main carriage, a motor mounted thereon, a driving shaft actuated by the motor, a driven shaft, means for actuating the driven shaft from the driving shaft, sprocket wheels mounted on the driving and driven shafts, elevators consisting of 90 elevator belts meshing with the sprocket wheels, and carriers for the elevator belts, means for effecting the adjustment of the elevators, and an adjustable supporting means for the elevators.

100 12. The hereinbefore described apparatus comprising a main carriage, a crane projecting beyond the end of the main carriage, a driving shaft journaled in bearings carried by the crane, a motor for actuating the driving shaft, a driven shaft actuated by the driving shaft, sprocket wheels mounted on the driving and driven shafts, and elevators consisting of elevator sides having elongated slots 105 therein, through which project the driving and driven shafts, guide blocks loosely mounted on the driving and driven shafts engaging with the walls of the elongated slots, sprocket wheels revolvable between the elevator sides, elevator belts passing around the 110 said sprocket wheels, elevator buckets pivotally connected to the elevator belts to be selectively tripped during the travel thereof, and friction brakes to arrest the travel of the elevator belts.

115 13. The hereinbefore described apparatus comprising a main carriage, a crane projecting beyond the end of the main carriage, a driving shaft journaled in bearings carried by the crane, a motor for actuating the driving shaft, a driven shaft actuated by the driving shaft, sprocket wheels mounted on the driving and driven shafts, and elevators consisting of elevator sides having an elongated slot 125 therein through which project the driving 130

and driven shafts, guide blocks loosely mounted on the driving and driven shafts engaging with the walls of the elongated slots, sprocket wheels revoluble between the elevator sides, elevator belts passing around the sprocket wheels, elevator buckets pivotally connected to the elevator belts to be selectively tripped during the travel thereof, friction brakes to arrest the travel of the elevator belts, a supporting means for the elevators, and means to adjust the supporting means during the adjustment of the elevators.

14. The hereinbefore described apparatus comprising a main carriage, a crane projecting beyond one end thereof, a track rail carried by the crane, a crane car mounted on the track rail, lifting and lowering cylinders, a tamping frame suspended from the lifting and lowering cylinders, tamping levers fulcrumed to the tamping frame, expanding cylinders actuating the tamping levers, means actuating the lifting and lowering cylinders, and means actuating the expanding cylinders.

15. The hereinbefore described apparatus comprising a main carriage, a crane projecting beyond one end thereof, a track rail carried by the crane, a crane car mounted on the track rail, lifting and lowering cylinders suspended from the crane car, a tamping frame suspended from the lifting and lowering cylinders, tamping levers fulcrumed to the tamping frame, blades connected with the tamping levers, expanding cylinders actuating the tamping levers, and means actuating the lifting and lowering cylinders and means actuating the expanding cylinders.

16. The hereinbefore described apparatus comprising a tamping mechanism consisting

of a tamping frame, tamping levers fulcrumed to the tamping frame, expanding cylinders for the tamping levers, and means for actuating the expanding cylinders.

17. The hereinbefore described apparatus 45 comprising a tamping mechanism consisting of a tamping frame, spring tensioned fulcrums supported by the tamping frame, tamping levers rockable on the spring tensioned fulcrums, and expanding cylinders for 50 the expanding levers.

18. The hereinbefore described apparatus comprising a tamping mechanism consisting of a tamping frame, spring tensioned fulcrums supported by the tamping frame, 55 tamping levers rockable on the spring tensioned fulcrums, blades for the tamping levers, and expanding cylinders for actuating the tamping levers.

19. The hereinbefore described apparatus 60 comprising a tamping mechanism consisting of lifting and lowering cylinders, pistons movable therein, piston rods for the pistons, compression springs engaging the pistons and cylinders, a tamping frame suspended from 65 the piston rods, spring tensioned fulcrums carried by the tamping frame, tamping levers rockable on the spring tensioned fulcrums, shovel blades connected to the lower ends of the tamping levers, expanding cylinders 70 actuating the expanding rails means for actuating the expanding cylinders, and means for actuating the lifting and lowering cylinders.
